STRAND TREATING APPARATUS AND METHOD

Original application filed March 7, 1929, Serial No. 345,077. Divided and this application filed
September 4, 1930. Serial No. 479,650.

This invention relates to an apparatus and method for treating strands of material which originally is in the form of numerous elongated entangled fibrous components, and 5 more particularly for loosening these components and forming the same into a lightly fluffed substantially uniform mass or mat. This application is a division of copending application Serial No. 345,077, filed March 10, 1929.

In accordance with the present invention, any desired flexible strands or fibers which are typically elongate and which originally may be rather firmly compacted and entangled or formed into irregular bunches may be loosened and lightly fluffed to provide a uniform mat or mass that may be subjected to any suitable succeeding operations or use. For example, this arrangement is 20 particularly advantageous in preparing excelsior, i. e. elongate flexible more or less curling strands of wood, so that the excelsior may be readily manufactured into artificial lumber comprising reticulated strands 25 bound by and coated with a suitable cementitious and protective agent, such as a magnesite cement. While the process and apparatus disclosed herein is broadly applicable to employment for the loosening and uniformly distributing of strands of practically any character, for purposes of convenience of illustration and description, the treatment of excelsior strands will be particularly referred to hereinafter. These strands are 30 ordinarily received in quite closely compacted bundles or bales, and preferably are first somewhat loosened and may then be cut; the bunches or entangled masses of the excelsior may then be broken up by a suitable 35 picking and/or combing means, thereafter being supplied to means for lightly fluffing the fibers so that they are substantially individually separated and uniformly distributed in light, non-adherent, non-entangled 40 engagement with each other. To permit the provision of a fluffed mass in this manner we preferably employ a movable duct or nozzle through which air under pressure is emitted to provide an oscillating high velocity concentrated jet which loosens and

separates the entangled mass and uniformly distributes the elongate strands of fibrous components in a suitable collecting passage, such for example as a chute which supplies the loose mass of material to a receiving belt 55 or any suitable receiving means.

In the accompanying drawing,

Fig. 1 is a side elevational view, somewhat diagrammatic in character and with parts in section, showing the arrangement of my 60 preferred strand fluffing apparatus;

Fig. 2 is an elevational view of a portion of this apparatus including the air nozzle and related parts; and

Fig. 3 is a top view of the air nozzle and 65 related parts.

The material which is to be loosened and fluffed ordinarily may be received in a more or less closely compacted and entangled or bunched condition, for example, bales of 70 excelsior may be broken open, and the excelsior fed by hand to the machine in irregular masses of varying sizes. Such material is designated in the accompanying drawing by the numeral 1, being disposed 75 upon a table 1^a, the edge of which is juxtaposed to the bite of a pair of rolls 3 and 4, one or both of which may be provided with suitable feed projections 5 in order to deliver the material from table 1^a to cutting 80 mechanism, designated in general by the numeral 6. This cutting mechanism is particularly desirable when the strands have a comparatively great length, and individual strands, being relatively curly, tend to have 85 several convolutions and accordingly have become very much entangled with each other. The cutting mechanism 6 is designed to cut such stranded material into shorter portions; for example, an average length 90 of from two to six inches has been found commercially satisfactory for the manufacture of excelsior lumber. The cutting mechanism is provided with a rotor 7 having segmental knives 8 that are adapted to cooperate with a fixed vertically disposed plate 10 in shearing the strands received from the rolls 3 and 4.

As indicated by the curved arrow in Fig. 1, the knives 8 rotate so that they tend to 100

cast the severed strands upwardly against a guide plate 13 which is extended over a lower supporting plate 13^a. Accordingly continued rotary movement of the cutter 7 causes the material to be fed between plates 13 and 13^a onto a suitable receiving belt 14, which, as shown, may be substantially horizontally disposed. The excelsior strands received by the belt 14 are still in a more or less irregularly bunched and entangled condition, and a feed roller 25 over the end of belt 14 cooperates with the latter in feeding this material to a picker. This mechanism may include a relatively large roll 17 having radially disposed teeth 19 projecting therefrom and adapted to engage the somewhat bunched strands as they pass from the roll 25 and belt 14. A cover plate 18 may be disposed over the roll 17 and may carry a comb 18^a which cooperates with the teeth 19 in loosening the bunched and entangled strands.

From the picker the loosened material which now is in a loosely entangled, non-uniformly distributed condition, falls into the upper end of an inclined passageway or chute 35. This portion of the mechanism is preferably provided with suitable means further to separate and to distribute the fibrous material evenly so that a substantially uniform loose or fluffed mat is provided.

The preferred arrangement for attaining this desirable result comprises a movable air nozzle 27 which has its open end projecting downwardly into the upper end of an inclined chute 35 and which is supplied with compressed air through a flexible duct 28, such as an air hose, which may be connected to any suitable source of air supply. Means is preferably provided to move the nozzle transversely of the chute 35, this means being illustrated more in detail in Figs. 2 and 3. For this purpose the axle 81 of roll 17 may be provided with an eccentric pin or crank 83 which is pivotally connected to a link 84. The opposite end of link 84 is articulated to one arm of a bell crank 85, the other arm of which is articulated to a transverse rod 86, this rod being disposed transversely of and somewhat above the upper end of chute 25. The ends of the rod 86 preferably are slidably received in suitable supporting elements or bearings 50. The intermediate part of rod 86 is pivotally connected, as designated by numeral 51, to a nozzle holder 87, the end of which is pivotally connected to a fixed support, for example an extension of the curved plate 18 over the picker. It is thus evident that rotation of the picker 17 causes the transverse movement of the nozzle 27 and accordingly air under pressure may be repeatedly supplied to each portion of the open end of the chute 35.

In the operation of apparatus of this character the stranded material may be received on the table 1^a in a more or less firmly entangled, closely bunched condition, for example the condition of excelsior when taken out of the conventional bale, and may then be sufficiently separated by hand to be fed between the rollers 3 and 4 to the cutting means 6. This means is somewhat effective in breaking up the bunched strands and in causing the average length of the strands to be much less than when originally received. Thus the occurrence of typically long, convoluted or extremely curly strands is avoided as the material leaves the cutter 6 and passes over the belt 14 to the picker. The latter includes the toothed roller 17 and comb 18^a which cooperate in opening up the smaller somewhat loosened bunches of stranded material, so that as the same are supplied to the chute 35 they may be readily acted upon and substantially completely separated by the action of the oscillating high velocity concentrated air jet emitted from the nozzle 27. The movement of this nozzle transversely of the chute is advantageous in causing the substantially uniform distribution of the fibrous material throughout the chute. For example, the strands directly in front of the nozzle are picked up and hurled against adjoining strands so that the loosened individual strands readily find their way to the regions where the stranded material is less densely distributed, whereby a substantially uniform distribution of the strands results. Thus the stranded material passing from the chute 35 to any suitable receiving means, such as a belt not shown, in the form of a lightly and substantially uniformly fluffed mat in which the strands are not typically entangled, but lightly engage one another.

I claim:

1. Apparatus of the class described, comprising an elongate strand receiving duct, means to deliver strands to an open end of the duct, and an air nozzle independent of said delivery means, said nozzle being movable across the open end of the duct and arranged to emit a high velocity concentrated air jet into the open end of the duct, at an angle to the plane of travel of said strand material through said duct, and driving means to move the air nozzle to and fro transversely of the duct.

2. Apparatus of the class described, comprising an elongate strand receiving duct, means to deliver strands to an open end of the duct, and an air nozzle independent of said delivery means, said nozzle being movable across the open end of the duct and arranged to emit a high velocity concentrated air jet into the open end of the duct, at an angle to the plane of travel of said strand material through said duct, and driving

means to move the air nozzle to and fro transversely of the duct, said driving means being operable in synchronized relation to the strand delivering means.

5 3. Apparatus of the class described, comprising a strand picker, a strand receiving duct having an open end arranged to receive loosened strands from the picker, and an air nozzle movable across the end of the duct 10 and arranged to emit a high velocity concentrated air jet into said duct at an angle to the plane of travel of said strand material through said duct.

15 4. A method of treating elongate entangled strand material to form a loosely fluffed mat of uniformly distributed strands disposed in substantially non-entangled engagement, which method comprises feeding the entangled strand material into an elongate passage, and concomitantly subjecting the moving mass of strand material to the action of an oscillating high velocity concentrated air jet which strikes said material at an angle to its plane of travel through 20 25 said passage, whereby the entangled strands are separated and uniformly distributed throughout said passage.

Signed by me at Boston, Massachusetts,
this 27th day of August, 1930.
